SUSPENDED GIRDER THE HORIZONTAL PROJECTION OF WHICH IS INCURVED

Yves Colombot, Saint-Cloud, France, assignor to Baudin-Chateauneuf, Chateauneuf-sur-Loire, Loiret, France, a French company

Filed Apr. 13, 1961, Ser. No. 102,685

Claims priority, application France Apr. 26, 1960
6 Claims. (Cl. 14—18)

The present invention concerns a suspended girder which is curved in a horizontal plane. Such a suspended girder may serve in particular for suspended railways so as to allow the latter to pass over large spans under excellent conditions for the connection of the track sections, which is a particularly difficult matter by reason of the high speed reached by trains on such tracks.

Briefly the invention includes a girder which is curved in a horizontal plane and is carried by cables supported by towers. Each carrier cable whose projection on a vertical plane is approximately a parabola, is developed on a warped surface passing through supporting points constituted by the upper ends of the corresponding towers and through the middle of the curved line defined by the girder. Means are provided for balancing thrusts arising in opposite directions in said girders under the action of the horizontal components of the forces to be considered.

This structure satisfies the object obtaining an incurved suspended girder provided, on the one hand, with the advantages of conventional suspended girders and on the other hand, with the further advantage of simplifying the connection between the two ends of the girder in different directions.

The invention has also for its object embodiments incorporating at least one of the following features:

Means adapted to balance the thrusts produced along the incurved girder, constituted by the actual natural resistance of the latter against flexion which is taken into account.

Abutment blocks anchored in the ground which serve as bearings for the two ends of the incurved girder and form means for balancing the horizontal thrusts produced in the girder.

The means for balancing the thrusts produced inside the incurved girder are constituted by one or more ties connecting the ends of the girder with each other.

Each tie is rectilinear and is carried, at intervals, by slings secured to the corresponding carrier cable.

The terminal towers slope upwardly and inwardly of the curve formed by the girder.

The connection between the suspension cable and the incurved girder is ensured by slings arranged normally to the girder and by a rigid connection in the middle of said girder.

According to a modification of the invention, the connection between the cable and the girder is ensured by slings which are oblique with reference to the longitudinal component of the girder with which they are connected.

The invention will be better understood by a reading of the following description, reference being made to the accompanying drawings showing by way of example, and by no means in a limiting sense, various embodiments of the invention. In said drawings,

FIG. 1 illustrates diagrammatically and in perspective view, a suspended bridge including several bays of which one has an incurved shape on a horizontal projection,

FIG. 2 is a detailed plan view of a modified embodiment of the incurved bay of FIG. 1,

FIG. 3 is a cross-section through line III—III of FIG. 2,

FIG. 4 is a side view of a further embodiment of the

2

invention incorporating the modification shown in FIG. 2 for a single bay structure.

FIG. 5 illustrates a modification of FIG. 4.

The suspended bridge illustrated in FIG. 1 includes an incurved bay designated, as a whole, by the reference number 1. The other bays 2, 3 and 4 are, for instance, bays having a rectilinear horizontal projection.

The incurved bay 1 forms an example of a suspended girder the horizontal projection of which is incurved according to the invention.

The girder is illustrated diagrammatically as comprising two curved beam members 8 and 9 as shown also in FIG. 2, while the carrier cables corresponding thereto are shown at 11 and 12. The curved beams are connected by horizontal bracings 18 and 19 to form the girder.

Each carrier cable, for example, cable 12, is connected between the upper corresponding ends 14a and 15a of the towers 14 and 15 and the middle of the shaped member 9 carried thereby. The upper ends of the towers are located inwardly of the base of the tower whereby the towers will slope upwardly and inwardly of the curved girder which can best be seen in FIGS. 2 and 3. The cable 11 is similarly associated with the towers 10 and 17 and shaped member 8. The cables 11 and 12 are curved and lie in warped surfaces passing through the corresponding upper ends of the towers and the middle of the associated shaped member. The cables have a projection in a vertical plane which is approximately of parabolic shape, as can be seen in FIGS. 4 and 5.

In the example illustrated in FIG. 1, the shaped member 9 is supported by the carrier cable 12, through the agency of slings such as 16 which are normal to a tangent to the shaped member with which they are connected.

Since the projection of the upper ends of the tower in the plane of the girder are offset from the curved members 8 and 9 (see FIG. 2) this will cause the slings 16 to slope upwardly and inwardly of the curved members 8 and 9 of the shaped member 9.

FIG. 2 shows the transverse elements 18 extending normally to the shaped members 8 and 9 and diagonal elements 19 extending between adjacent transverse elements.

In the embodiment illustrated in FIG. 1, the actual resistance of the incurved shaped members 8 and 9 against flexion is sufficient alone for the balancing and compensation of the horizontal thrusts appearing in the girder under the action of the resultant of the forces to which said girder is subjected.

In another embodiment, there are provided one or more ties such as 21 (FIGS. 2, 3 and 4) interconnecting the two ends of the incurved girder 9. Said tie is rectilinear and extends in the horizontal plane of the girder. It is carried by slings such as 22 connecting it with the corresponding carrier cable, 12 for instance.

The arrows f1 of FIG. 4 show by way of example tensile stresses exerted by the tie 21 for compensating for the thrusts arising in the incurved girder.

The arrows such as f2 show the resultant of the vertical forces absorbed by the terminal bearing parts 24 and 25 of the girder. Lastly the arrows such as f3 show the tensile stresses exerted by the carrier cables 11 and 12 on the anchoring blocks 27 and 28.

In the modification illustrated in FIG. 5, the thrusts exerted along the incurved girder are balanced by the resistance afforded by the two anchoring blocks 31 and 32 which serve both as supports and abutments for the ends of the girder. The resultant of the vertical forces is again illustrated by the arrows f2, while the thrusts along the incurved girder which are balanced by the stops or abutments considered are indicated by the ar-

rows f4. The anchoring blocks for the carrier cables are shown, as above at 27 and 28.

By way of a modification also, whereas the slings 16 connecting the carrier cables 11 and 12 with the shaped members 8 and 9 of FIG. 1 are directed normally to the corresponding member forming part of the girder while the middle of the carrier cable is secured to the middle of the corresponding shaped member, in contradistinction, in the case of FIGS. 4 and 5, the slings 33 are oblique with reference to the cable without the middle of the carrier cable being necessarily secured to the girder.

Obviously, the invention is not limited to the embodiments described and illustrated by way of example, and various modifications may be brought thereto without unduly widening the scope of the invention as defined in the accompanying claims.

I claim:

1. A suspension bridge comprising a supporting girder curved in a horizontal plane, end towers angularly disposed relative to each other in a horizontal plane, spaced carrier cables extending between said towers and having points of connection to said towers which are spaced laterally of the sides of the girder in a direction inwardly of the curve of the girder, and spaced slings connecting said carrier cables to said curved girder, the carrier cables having a parabolic projection in a vertical plane and said slings being inclined upwardly and inwardly from said girder.

2. A suspension as claimed in claim 1 wherein the

slings lie in planes perpendicular to the tangent to the girder at the point of connection between the slings and the girder.

3. A suspension as claimed in claim 1 wherein the slings lie in planes which are obliquely inclined to the tangent to the girder at the point of connection between the slings and the girder, in a direction towards the center of curvature of the girder.

4. A suspension as claimed in claim 1 comprising anchoring block means supporting each of the ends of the girder and including thrust surfaces for resisting forces developed by the carrier cables in both a horizontal and a vertical direction.

5. A suspension as claimed in claim 1 comprising a straight tie member extending in the plane of the girder between the opposite ends thereof and connected thereto, and spaced slings connected between one of said cables and the tie member.

6. A suspension as claimed in claim 5 comprising anchoring block means at both ends of the girder supporting the same.
